DEVICE FOR WINDING UP A CONTINUOUS LENGTH OF FLEXIBLE MATERIAL

Alten E. Whitecar, Westville, N.J., assignor to Smith Kline & French Laboratories, Philadelphia, Pa., a corporation of Pennsylvania

Filed Mar. 20, 1961, Ser. No. 96,915

1 Claim. (Cl. 242—68.1)

This invention relates generally to take-up devices and particularly to means for winding up tape as it is payed out by a utility.

An object of the invention is to provide such means having a normal operating capacity exceeding the rate at which the tape is payed out by said utility.

Another object is to provide reel driving means manually adjustable during the winding operation to selectively increase the effective coupling between said driving means and reel as required by reason of the progressively increasing weight of material wound upon said reel.

Another object of the invention is to provide a knock-down reel utilizing a disposable central core and permanent flange plates respectively at opposite ends of said disposable central core.

Other objects of the invention will become apparent when the following specification is read with reference to the accompanying drawings, in which:

FIGURE 1 is an elevation of apparatus construed in accordance with the invention;

FIGURE 2 is a plan view of the apparatus shown in FIGURE 1;

FIGURE 3 is an enlarged section on the plane indicated by line 3—3 of FIGURE 1;

FIGURE 4 is a section on the plane indicated by line 4—4 of FIGURE 3;

FIGURE 5 is an enlarged section on the plane indicated by line 5—5 of FIGURE 2;

FIGURE 6 is a section on the plane indicated by line 6—6 of FIGURE 5, showing the friction clutch disengaged; and

FIGURE 7 is an enlarged section on the plane indicated by line 7—7 of FIGURE 1, showing the friction clutch engaged.

Apparatus embodying the present invention comprises a utility having a housing 12 mounting a horizontally extending shaft 14 over which is fitted a compression coil spring 16, a pair of holders 18 and a nut 20. Affixed to the housing 12 is a bracket 22, and suitably mounted between the bracket and the housing are a pair of horizontally extending drive rollers 24. Below the drive rollers, between the bracket 22 and the housing 12, are suitably mounted a pair of horizontally extending shafts 26 respectively mounting coating cutter parts 28 and 30 and a pair of horizontally extending shafts 32 respectively mounting coating cutter parts 34 and 36.

The apparatus also comprises a conveyor, generally designated 38, including head and foot pulleys 40 and a belt 42. At the end of the conveyor is a container 44 for receiving work from the conveyor.

Mounted upon the shaft 14 is a roll of tape 46 made of cellophane or the like. The tape itself, designated 48, extends downwardly from the roll 46 between drive rollers 24, freely through an opening 50 in the bracket 22, between cutter parts 28 and 30 and cutter rollers 34 and 36, and freely through an opening 52 in the bracket 22. Strips of tape cut to the desired size by cutter parts 28 and 30 and cutter rollers 34 and 36 are indicated at 54. The selvage, indicated at 56, extends over a guide 58 to a take-up device, generally designated 60.

The take-up device comprises a motor 62 driving a

2

change speed unit 64 from which extends a drive shaft 66. Mounted upon axially spaced portions of the shaft 66 are inner and outer ball bearing units, generally designated 68, each of which units includes an inner race 70 affixed to the shaft 66, and outer race 72 and balls 74. Mounted upon the ball bearing units 68 is a reel mounting device, generally designated 76.

The device 76 includes inner and outer annuli 78 respectively affixed to the outer ball bearing races 72. Embracing the annuli 78 is a hollow cylindrical member 80 secured by screws 82. Affixed to the outer end of the member 80 is a plate 84 into which is threaded one end portion of a rod 86 fitted with a lock nut 88 and a wing nut 90. The rod 86 is coaxially related to the shaft 66 and extends in longitudinal continuation thereof.

Mounted upon the device 76 is a reel, generally designated 92, which reel is provided with a hollow cylindrical core 94 slidably fitted over the member 80 and with inner and outer flange plates respectively designated 96 and 98. The inner flange plate 96 fits over the shaft 66 and abuts the inner end of the reel mounting device and the inner end of the core 94, while the outer flange plate 98 fits over the rod 86 and abuts the outer end of the core 94. The inner flange plate 96 is affixed to the annulus 78.

Mounted upon the shaft 66 is a friction clutch, generally designated 100, which clutch comprises a pin mount 102 affixed to the shaft 66. One end of the pin mount is provided with a slit 104 and fitted with a screw 106 for affixing the pin mount to the shaft 66. The pin mount carries a pair of guide pins 108 extending parallel to the shaft 66.

The clutch also comprises a leaf spring mount 110 slidably fitted over the shaft 66 and guide pins 108. At each end of the mount is a leaf spring 112 affixed to the mount by a screw 116 projected through a washer 114. The leaf spring 112 and the washer 114 are notched, as at 118, to accommodate the associated guide pin 108. Thus the leaf spring 112 is secured against rotation about the axis of the screw 116. Carried by the free end of the leaf spring 112 is a nylon friction pad 120 secured to the leaf spring by a pin 122.

Fitted over the shaft 66 is a sleeve 124 affixed to the shaft 66 by a set screw 126, and threaded upon the sleeve 124 is a finger piece 128, which finger piece normally abuts the leaf spring mount 110.

In order to load the apparatus, the nut 20 is turned off shaft 14 and the outer holder 18 is slipped off the shaft. The roll 46 of tape is then slipped over shaft 14, and the outer holder 18 and nut 20 are replaced. The coil spring 16 acts to bias the roll 46 and holder 18 against the nut 20. The leading end of the tape 48 is now manually threaded between drive rollers 24, through the opening 50 in the bracket 22 between cutter parts 28 and 30 and cutter rollers 34 and 36 and through the opening 52 in the bracket 22. A few feet of the tape 48 are manually drawn from the roll 46, whereupon the cutter parts 28 and 30 coact to slit the tape longitudinally, while the cutter rollers 34 and 36 coact to cut the tape transversely. The finished pieces of work 54 drop through the bracket opening 52 onto conveyor belt 42 and are carried to the container 44. The selvage strip 56 passes freely between cutter part 28 and cutter roller 34 and over guide 58 to the reel 92. The end of the strip is affixed to the core 94 of the reel.

The take-up device 60 is now adjusted by turning the finger piece 128 till it bears upon the leaf spring mount 110 and shifts the same axially upon the pins 108 till the leaf springs 112 are deflected and the friction pads 120 are caused to bear upon the inner flange plate 96. Thus the reel 92 and the reel mounting means 76 are clutched to shaft 66.

Now the winding operation is commenced. The rollers 24 draw the tape 48 from roll 46 preferably at a predetermined constant average number of feet per minute. Reel mounting means 76, reel 92 and friction clutch 100 turn with shaft 66, the initial number of revolutions per minute preferably being at least sufficient to take up the selvage as it is separate from tape 48.

As more and more selvage accumulates on the core 94, the diameter of the roll of material on the core 94 increases, and there is a tendency for lost motion to occur through slippage between pads 120 and the flange 96. While the coupling between the shaft 66 and the reel 92 must be tight enough for actuation of the reel 92, it must be loose enough to permit such slippage. Eventually, the weight of material accumulated on the reel overcomes the clutching effort and makes re-adjustment necessary. Without terminating the winding operation, the finger piece 128 is manually turned momentarily to bring increased pressure on the leaf spring mount 110, which shifts axially on the pins 108 toward the pin mount 102, whereupon leaf springs 112 are deflected further and exert more pressure on the pads 120, thereby increasing the clutching effort and the effective driving power. Normally, once or twice during a winding operation the coupling between the clutch 100 and reel 92 must be made tighter to accommodate the progressively increasing weight of material accumulated upon the reel, but care must be exercised to avoid making the coupling so tight that the slippage necessary to accommodate the progressively increasing diameter of the roll of material cannot occur.

When the supply of tape has been exhausted operation of the apparatus is terminated. Wing nut 90 is threaded off the rod 86, the outer flange plate 98 is removed and the core 94, with the selvage 56 wound thereon, is slipped off the reel mounting means 76 and discarded. A fresh core is mounted upon reel mounting means 76, and flange 98 and wing nut 90 are replaced. It will be noted that the new core may be either longer or shorter than the core 94 which it replaces, the same flanges 96 and 98 and reel mounting means 76 are used. Now the same procedure as already outlined is repeated.

It will be understood, of course, that the present invention is susceptible of various modifications which may be made without departing from the general principles of the invention. Accordingly, it is intended to claim the same broadly as well as specifically, as indicated by the appended claim.

What is claimed is:

A take-up device for winding a continuous length of flexible material comprising in combination a constant speed drive means having a drive shaft, a bearing assembly secured on said shaft and fixed against axial movement along said shaft, a first disc fixed to said bearing assembly, a cylindrical core removably supported by said bearing assembly and having one end abutting said first disc, a second disc abutting the other end of said core removable clamping means secured to said bearing assembly and engaging said second disc for removably clamping said discs and core in axially abutting relationship so as to form a reel for winding said material, a member mounted for rotation with and axial shifting movement upon said shaft adjacent said first disc, spring means carried by said member, friction engaging means carried by said spring means for frictionally engaging said first disc, and manually adjustable means mounted on said shaft for rotation therewith and for axial movement into engagement with said member for increasing the frictional engagement between said engaging means and said first disc during the winding of said material upon said reel.
